FIG. 1 is a front, left, and bottom perspective view of a charging station for mobile device, showing my new design; FIG. 2 is a rear, right, and top perspective view thereof; FIG. 3 is a front elevational view thereof; FIG. 4 is a rear elevational view thereof; FIG. 5 is a left elevational view thereof; FIG. 6 is a right elevational view thereof; FIG. 7 is a top plan view thereof; FIG. 8 is a bottom plan view thereof; and, FIG. 9 is a detailed view taken from the encircled portion labeled "9" in FIG. 1.

The short-dash and long-dash broken lines and the number 9 in FIGS. 1 and 9 denote the boundaries of the detail areas and form no part of the claimed design. The even-spaced broken lines in the drawings depict portions of the charging station for mobile device that form no part of the claimed design.
